WATER ANTENNA

Nils E. Lindenblad, Princeton, N. J., assignor to Radio Corporation of America, a corporation of Delaware

Application November 2, 1953, Serial No. 389,527

12 Claims. (Cl. 343—767)

This invention relates to antennas, and more particularly to antennas formed in the surface of a body of water.

It is an object of my invention to devise an antenna formed in the surface of a body of water. Further objects are to provide simple and practical means of so forming slot antennas, and to provide antennas giving desired radiation patterns.

Slot antennas formed in metal are known. In the case of a sheet of metal constituting a plane conductive surface, provision of an open slot can form an antenna. It is also known to provide a backing shell, which gives an open slot backed by a cavity with conductive wall surfaces. When leads of opposite polarity are connected at the opposite sides of the slot or of the backing cavity, and radio frequency alternating current is applied, radiation takes place from the opposite edges of the slot. The strongest radiation fields usually extend transverse to the direction of the slot. Desirably the slot should be about a half wave-length long. The backing cavity should be about a quarter wave-length deep, and less than a quarter wave-length wide. Slot antennas could therefore range from very large structures for low frequencies, which have long wave lengths, to very small structures for high frequencies, which have short wave lengths.

The characteristics of slot antennas and their dimensional variations are known in the art. See for example "Slot Antennas" by Nils E. Lindenblad in the Proceedings of the IRE of December 1947, and "Antennas" by John D. Kraus, McGraw-Hill Book Co., Inc., New York, N. Y., 1950, pp. 353-381.

My invention involves using the surface of a body of water, such as the ocean or a lake, for the plane conductive surface of a slot antenna, and forming the slot at the surface of the water and its backing cavity in the body of the water by displacement with a suitably shaped dielectric body. The provision of the dielectric discontinuity in the water to form a slot antenna is embraced in my invention, as is also the means for displacing the water to form an antenna. Salt water is best adapted for use of my invention, but most bodies of fresh water have sufficient conductivity for the purpose.

In the drawings.

Fig. 1 is a perspective view of an antenna formed in the surface of a body of water, by for example a large wooden box suitably supported in partially submerged position, as by piles driven in the bottom of a lake;

Fig. 1a is a cross-section of same viewed in the direction of the arrow A in Fig. 1;

Fig. 2 is a sectional view of the end portion of a pneumatic life raft incorporating an antenna in accordance with my invention;

Fig. 2a is an elevation of same;

Fig. 3 shows, in section, an inflatable floating device forming a sea-water slot antenna;

Fig. 3a is an elevation of same;

2

Fig. 4 shows a paddle designed to give a water slot antenna for high frequencies;

Fig. 5 shows in horizontal cross section, an annular form for omnidirectional radiation; and

Fig. 5a is a perspective view of the annular form.

Referring to Figs. 1 and 1a, I provide a box 10 of dielectric material which I partially submerge in the water. It may be made for example of wood or plastic, and it may be hollow or solid. This will be a choice of convenience, depending largely on size, which depends upon frequency used. In preferred form its length is half the wave length to be employed, its submerged depth is half its length, and its thickness is considerably less than its depth. For example, for a frequency of 1,000 kilocycles it would be almost 500 feet long, have a submerged depth approaching 250 feet, and a much smaller thickness. For a frequency of 100 megacycles it would be a little under 5 feet long, of about 2½ feet submerged depth, and of any thickness less than 2½ feet, as for example 6 inches. As shown in Figs. 1 and 1a it is a large wooden box, weighted as at 19, and held in place by piles 11. The box could be freely floating, anchored, or towed, rather than supported by piles. Conductive areas or patches 12, 13 are provided on its opposite outer sides, providing contact with and conduction to the water. Leads 14, 15 connect the patches to a coaxial cable 16 which leads to a transmitter or receiver, not shown. A seal 17 is provided where the cable passes through the box wall. In this form as in the others, the submerged portions of the walls could be all of sheet metal if desired instead of having small conductive areas, provided that a dielectric cavity is formed within the body by non-conductive solid or air space. The conductive areas or patches 12, 13 should be located at a height to match the impedance of the antenna to that of the transmission line cable.

Fig. 2 illustrates my invention incorporated in a pneumatic life raft. Here I have shown a portion of a life raft 20, having tube 20a and bottom 20b. On the under side of the pneumatic tube is formed a downwardly extending pouch 21, of dimensions like the first embodiment, namely twice as long as it is deep, and thinner than its depth. A hole 21a allows the pouch to be distended by air pressure when the tube is inflated. On the outer surfaces of the pouch 21 are provided two conductive areas or patches 22, 23 connected by leads 24, 25 through cable 26 to a radio transmitter or receiver, not shown, which may be located on the raft. The water around this displacing pouch forms in effect a slot antenna.

In Fig. 3, I have shown a portable floating body which will provide a slot antenna in the water. An elongated balloon 30 of hour-glass cross-section has a top float portion 30a and a bottom displacement portion 30b. A rigid yoke 31, forming a long, narrow loop, holds the slot dimension. When inflated through valve 37 and with a suitable weight 39 in the bottom, it will float with its waist just below the surface. In this form, as is possible in the others, the backing cavity is thicker than the width of the slot. As known in the art, this has radiation characteristics which are preferable for some purposes. Here again, conductive areas 32, 33 provide contact with the sea water at the opposite sides of the cavity.

While this antenna might be externally fed as in the other embodiments, it may be designed as a self-contained radiator, for use as a floating beacon for example. For such use I have shown the submersion weight as batteries 39, connected to a radio frequency oscillator 38 which is connected by leads 34, 35 to the conductive areas. The oscillator, indicated by block 38, may be physically mounted in any convenient manner within the

displacement portion, and may be switched on by any desired switch-throwing expedient.

Fig. 4 illustrates a simple way of providing a slot antenna for higher frequencies. Here a wide, thin paddle 40 of wood or other dielectric, with handle 40a and blade 40b, has conductive areas 42, 43 on opposite sides of the blade. These are connected by leads 44, 45 and cable 46 to a radio transmitter or receiver. Immersing the paddle to a depth about half its width, with the conductive patches submerged, provides a slot antenna.

In Figs. 5 and 5a I have illustrated my invention embodied in an annular form to give an omnidirectional radiation pattern. Here a cylindrical ring 50 of plastic or other dielectric material is partially submerged in the water. Its outside diameter may desirably be one half wave length, its top projects above the surface to keep the ring slot open, while its specific gravity is so chosen as to give it a depth of immersion of one quarter wave length, and its shell thickness is less than a quarter wave length.

Exterior conductive areas or patches 52, approximately 120° apart, and corresponding interior conductive patches 53 approximately 120° apart, are fastened to the surfaces of the cylindrical ring and are in direct contact with the water outside the ring and inside the ring respectively. The outside surface patches 52 are fed by one set of inner leads 54, which join to become the inner conductor of a coaxial cable 56. The inside surface patches 53 are fed by a set of leads 55 which may constitute outer conductors around leads 54. These join to become the common outer conductor of a coaxial cable 56. In all cases, lines other than coaxial cables may be used if permitted by the frequencies being employed.

Other antenna configurations may be provided to give desired radiation patterns and to suit the wave lengths employed and conditions of use. Such antennas may be used wherever suitable. They have advantages for example for emergency life-boat use, for use as a float from a submerged submarine, and for use wherever a body of water is available and construction of elevated structures or metal structures is difficult or undesirable.

What is claimed is:

1. A slot antenna for radiating or receiving radio frequency energy propagated through the air and utilizing a body of water as a conductive medium, comprising, a dielectric body partially immersed in the body of water to form a non-conductive cavity extending down into the water from the surface thereof, and antenna leads conductively coupled to the water at opposite sides of the dielectric body.

2. A slot antenna as defined in claim 1 wherein said dielectric body has length and thickness in the horizontal plane, and is immersed in the water to a depth intermediate said length and said thickness.

3. A slot antenna as defined in claim 1 wherein said antenna leads are conductively coupled to the water thru

conductive patches on the opposite sides of said dielectric body.

4. A slot antenna as defined in claim 1 wherein said dielectric body has a smaller cross-sectional area at the surface of the water than it has below the surface.

5. A slot antenna as defined in claim 1, and in addition, a power supply and a radio frequency oscillator mounted within said dielectric body, and output leads coupled between the output of said oscillator and said antenna leads.

10. 6. A slot antenna as defined in claim 1 wherein said dielectric body includes an enlarged inflated portion floating on the surface of the water.

15. 7. A slot antenna as defined in claim 1 wherein said dielectric body is shaped as a paddle.

8. A slot antenna as defined in claim 1 wherein said dielectric body is annular, and said antenna leads are conductively coupled to the water at the inner and outer sides of said body.

20. 9. A slot antenna as defined in claim 1 wherein the cross-sectional area of said dielectric body at the surface of the water is elongated and has a length substantially equal to a half-wavelength at the operating frequency of the antenna.

25. 10. A slot antenna for radiating or receiving radio frequency energy propagated through the air and utilizing a body of water as a conductive medium, comprising, a hollow dielectric body partially immersed in the body of water to form a non-conductive cavity extending down into the water from the surface thereof, and antenna leads conductively coupled to the water at opposite sides of the dielectric body.

30. 11. A slot antenna comprising a body of conductive fluid having therein a dielectric space to form a slot at the surface of said fluid, and a pair of antenna leads positioned at opposite sides of said space to electrically contact said fluid.

35. 12. A slot antenna for radiating or receiving a radio frequency signal through the air and adapted to utilize 40 a body of water as a conductive medium, comprising a dielectric body adapted to be at least partially immersed in said body of water to form a non-conductive cavity extending down into said water from the surface thereof, electrodes on opposite sides of said dielectric body for contacting said water, and leads coupled to said electrodes for applying thereto or deriving therefrom a radio frequency signal.
